UNITED STATES PATENT OFFICE.

ADELBERT M. FOSTER, OF CHICAGO, ILLINOIS.

DESIGN FOR A BOTTLE.

SPECIFICATION forming part of Design No. 18,309, dated May 15, 1888.

Application filed March 14, 1888. Serial No. 267,188. Term of patent 14 years.

To all whom it may concern:

Be it known that I, ADELBERT M. FOSTER, a citizen of the United States, residing at Chicago, in the county of Cook and State of Illinois, have invented a new and original Design for a Bottle, set forth in the annexed specification, reference being had to the accompanying drawings, forming a part thereof.

Figure 1 is a side view of said new design, showing the three plane surfaces 1, 2, and 2.

Fig. 2 is a transverse sectional view showing the conformation.

The body of the bottle consists of a bottom bounded upon one side by a cylinder semi-elliptical in form, the other three sides being plane surfaces, and which consist of three rectangular parallelograms forming a semi-hexa-

gon, and marked 1, 2, and 2, respectively. The four sides of said bottle terminate at the top or shoulder of the bottle, which is slightly convex to where it meets the neck, the same being of ordinary form.

I claim—

The design for a bottle herein shown and described, the same consisting of a bottom with a semi-elliptical cylinder upon one side, the other three being the plane surfaces 1, 2, and 2, the same being almost equal rectangular parallelograms, all terminating at a slightly convex top and neck of ordinary form.

ADELBERT M. FOSTER.
